(57) **CLAIM**

The ornamental design for a mirror as shown and described.

DESCRIPTION

FIG. 1 is a front, left, top, perspective view of a mirror
showing my new design;

FIG. 2 is a rear, right, bottom, perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, left, top, perspective view of the mirror,
shown in an extended configuration;

FIG. 10 is a front, left, top, perspective view of the mirror
thereof, shown in a rotated configuration; and,

FIG. 11 is a front, left, top, exploded perspective view of the
mirror.

The dash-dash broken lines in the drawings depict portions
of the mirror that form no part of the claimed design.

1 Claim, 11 Drawing Sheets
